UNITED STATES PATENT OFFICE.

EDMOND W. T. RICHMOND, OF ROMFORD, ENGLAND.

DESIGN FOR A GAS-STOVE.

SPECIFICATION forming part of Design No. 33,881, dated January 8, 1901.

Application filed December 11, 1900. Serial No. 39,561. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the body portion A, having bulged sides a, the fronts of which sides are ornamented by leaves 15 a', the central opening B, in rear of which there is a corrugated plate b, the front top portion C above the opening, having the foliated ornamentation c, the back top portion

D, having the central foliated ornamentation d, arranged between and projecting above 20 foliated ornamentations d' on opposite sides of it, and the ornamental portion E below the central opening.

The top of the body portion consists of ornamental open-work, and there is a circular 25 cap G having a convex upper portion with foliated ornamentations.

I claim—

The design for a gas-stove, substantially as herein shown and described.

In testimony whereof I have hereunto subscribed my name.

EDMOND W. T. RICHMOND.

Witnesses:
